UNITED STATES PATENT OFFICE

171,611

INVERTIBLE DOLL

Marjorie Moyer, Tully, N. Y.

Application January 23, 1953, Serial No. 23,274

Term of patent 7 years

(Cl. D34—4)

To all whom it may concern:

Be it known that I, Marjorie Moyer, a citizen of the United States, residing at Tully, in the county of Onondaga and State of New York, have invented a new, original, and ornamental Design for an Invertible Doll, of which the following is a specification, reference being had to the accompanying drawing, forming part thereof.

Figure 1 is a front elevational view of an invertible doll in its upright position showing my new design;

Figure 2 is a rear elevational view thereof in the upright position;

Figure 3 is a front elevational view of the doll in the inverted position; and

Figure 4 is a rear elevational view of the doll in its inverted position.

I claim:

The ornamental design for an invertible doll, as shown.

MARJORIE MOYER.
